UNITED STATES PATENT OFFICE.

JACOB T. JOHNSON, OF KNOXVILLE, TENNESSEE.

BOTTLE.

SPECIFICATION forming part of Letters Patent No. 655,872, dated August 14, 1900.

Application filed September 15, 1899. Serial No. 730,604. (No model.)

To all whom it may concern:

Be it known that I, JACOB T. JOHNSON, a citizen of the United States, residing at Knoxville, in the county of Knox and State of Tennessee, have invented a new and useful Bottle, of which the following is a specification.

The invention relates to improvements in bottles, jars, and analogous receptacles.

The object of the present invention is to improve the construction of bottles, jars, and analogous receptacles, more especially the means for closing the same, and to provide a simple, inexpensive, and efficient construction whereby the closure of such a receptacle may have either a sliding or an interlocking connection with the neck of the receptacle, as desired or as the contents may require.

The invention consists in the construction and novel combination and arrangement of parts hereinafter fully described, illustrated in the accompanying drawings, and pointed out in the claim hereto appended.

In the drawings, Figure 1 is a vertical sectional view, partly in elevation, showing a cap-closure having a sliding connection with the exterior of the neck of a bottle. Fig. 2 is a similar view, showing the cap-closure having an interlocking connection with the neck. Fig. 3 is a sectional view, partly in elevation, showing the cap applied to a jar.

Like numerals of reference designate corresponding parts in all the figures of the drawings.

5 designates the neck of a bottle which is provided on its exterior with screw-threads 6, located at a point below the top of the neck, and the latter is provided with a smooth upper portion 7, located above the screw-threads 6 and adapted to be engaged by a cap-closure 8, as illustrated in Fig. 1 of the accompanying drawings, to provide a sliding connection with the neck.

The engaging face of the cap-closure, which is rendered elastic by the means hereinafter described, is adapted to have the screw-threads 6 embedded in it when the cap-closure is arranged as illustrated in Fig. 2 to provide an interlocking connection between it and the neck of the bottle 5. The neck of the bottle 5 is cylindrical, and the screw-threads 6 pro-

ject beyond the plane of the smooth upper portion 7 in order to interlock with the cap-closure 8.

The cap-closure 8, which is preferably constructed of sheet metal or other suitable material, is provided with an elastic lining 9, of cork or any other suitable material, which will enable the cap-closure to engage either the smooth upper portion or the threaded lower portion of the neck of a bottle or analogous receptacle, and the said lining, which may be arranged only on the vertical walls of the cap-closure, is preferably extended over the top of the same, as illustrated in the accompanying drawings. The cap is 60 adapted to form a closure for a jar 10, which is provided with a cylindrical neck 11, shown in side elevation in Fig. 3, and provided with a lower threaded portion 12 and an upper smooth portion 13. The cap-closure 14, which 70 is shown in engagement with the threads, as well as with the smooth upper portion, is provided with an elastic lining 15, which may be secured within the cap-closure by any suitable means.

It will be seen that the improvements herein shown and described are applicable to bottles, jars, and analogous receptacles and that the cylindrical neck with the smooth upper portion and the lower threaded portion enables the same cap-closure to be employed for effecting either a sliding or an interlocking connection with the receptacle at the option of the user. It will also be apparent that when the cap-closure is engaged only with the smooth upper portion of the neck the connection is as tight as that effected in an ordinary bottle with an ordinary cork and that when the cap-closure is engaged with the screw-threads it is enabled to resist great internal pressure and may be readily removed and replaced. Furthermore, it will be seen that bottles may be shipped with the cap-closures engaging the lower threaded portions and that the cap-closures will engage liquid-tight the smooth upper portion after having engaged the lower threaded portion.

What is claimed is—

The combination of a receptacle having a cylindrical neck practically of the same diam-

eter throughout its length provided with a smooth upper portion and having a threaded lower portion, the threads slightly projecting beyond the plane of the face of the smooth portion and a practically-cylindrical yielding cap-closure having an elastic engaging face and its threaded surface adapted to engage liquid-tight the smooth upper portion after having engaged the lower threaded portion,

substantially as and for the purpose described.

In testimony that I claim the foregoing as my own I have hereto affixed my signature in the presence of two witnesses.

JACOB T. JOHNSON.
